(57) **CLAIM**

The ornamental design for a cabinet lock, as shown and described.

DESCRIPTION

FIG. 1 is a front, right, top perspective view of a cabinet lock, showing my new design;

FIG. 2 is a rear, left, bottom perspective view thereof;

FIG. 3 is a front elevational view thereof;

FIG. 4 is a rear elevational view thereof;

FIG. 5 is a left-side view thereof;

FIG. 6 is a right-side view thereof

FIG. 7 is a top plan view of the enlarged scale thereof;

FIG. 8 is a bottom plan view of the enlarged scale thereof;

FIG. 9 is an enlarged view of detail 9 in FIG. 5; and,

FIG. 10 is an enlarged view of detail 10 in FIG. 6.

The dashed broken lines in the figures are for the purposes of illustrating portions of the cabinet lock that form no part of the claimed design.

The dash-dot-dash broken lines are for notating enlarged views and form no part of the claimed design.
